APPARATUS FOR ABRADING

Pierre de Vitry d'Avaucourt, Bainbridge, Pa.

Application June 3, 1947, Serial No. 752,115

10 Claims. (Cl. 51—131)

1

This invention relates to an apparatus for abrading and, more particularly, to an apparatus for generating surfaces on lenses and other similar articles. It is particularly useful in rough grinding of lens blanks.

In the generation of surfaces on lens blanks, either concave or convex, the blank is rotated with respect to the grinding element, commonly referred to as a lap, the lap and blank rotating about axes of rotation inclined one with respect to the other. In grinding plane or plano surfaces, the axes are parallel. Mechanism is provided on such generating machines for adjusting the angle of inclination between the axis of rotation of the lens blank and the annular lap to vary the radius of curvature formed on the surface of the blank and mechanism is also provided for transversely moving the blank and lap relative to one another to make possible the generating of concave and convex surfaces with the same lap.

An object of my invention is to provide a machine incorporating the two adjustments mentioned above in combination with mechanism for adjusting the position of the lens blank laterally of lap. With the machine of this invention, it is possible to quickly adjust the lap and lens blank holder in three directions to thereby bring the lap and blank into a position where the lap will engage the blank along a line which extends from edge to edge of the blank and passes through the axis of rotation of the blank. By provision of such an apparatus, it is possible to double the output of the machine because grinding is accomplished on both sides of the axis of rotation of the blank along a line which extends from edge to edge of the blank rather than from the axis of rotation to one edge as is the common practice.

It has been the general practice in this art to remove the lens blanks from the lens holder by hand, the operator generally using a fingernail to lift the blank by engagement with the edge thereof. This is not only hazardous, but is extremely time consuming. It is an object of my invention, therefore, to provide an apparatus which may be incorporated in a standard grinding machine which will be effective for quickly, conveniently, and with safety removing the lens blank from the lens holder and for extracting the blank from the removing means so that the same may be discharged from the machine by the operator with a simple motion. This also permits the operator to work with both hands and speeds up the operation of the abrading process.

2

A further object of my invention is to provide a simple, quick-acting brake for the lens holder spindle. It is common practice to use magnetic brakes and the like on the spindle, but these require complicated and expensive mechanism; whereas, according to the present invention, a very simple braking arrangement is combined with the lens picker.

Another object of my invention is to provide a combined mechanism for removing the lens blank from the lens holder and for braking the mechanism which rotates the lens holder. Thus with the machine of the present invention, it is possible for the operator to stop the rotation of the lens holder, mechanically pick out the lens blank, and insert a new lens blank in a small fraction of a minute. The prior practice has been to remove the lens blank after the spindle has stopped rotation and since the spindle is rotating at a relatively high speed, the inertia will cause the rotation to continue for a substantial length of time.

Another object of my invention is to provide for automatically establishing a supply of coolant to the lens blank and lap during the grinding operation and for cutting off the supply of such coolant automatically upon completion of the grinding cycle. A still further object is to combine the coolant control with means for automatically starting and stopping the power supply for the lens holder spindle. Thus the whole mechanism is automatic in operation and provides the utmost safety for the operator. When the lap is in grinding position, the motor which rotates the lens holder spindle is automatically started, and the supply of the coolant is fed to the surface of the lens blank and to the grinding surface. The supply of coolant continues until the grinding operation is completed; whereupon, the supply of coolant is discontinued and the power supply for the lens holder spindle is stopped.

Common practice in the prior art had been to provide the lens chuck with a conical spindle engaging surface and to provide separate chucks for receiving blanks of different sizes and also for receiving blanks having a concave surface to be ground and others for blanks having a convex surface to be ground. This necessitates a large number of chucks and also requires that the chuck be carefully adjusted into its conical holder. Another object of my invention, therefore, is to provide a universal chucking arrangement which will receive and hold lens blanks having either concave or convex surfaces to be ground, the chuck being rotatable through 180°

to permit the reception of blanks of different sizes on one side or the other thereof.

Machines now on the market for lens grinding are provided with ball bearing thrust arrangements. It has been found in the operation of such machines that the spindle will not run absolutely true due, it is believed, to the fact that the race which receives the balls will wear unevenly, and, as a consequence, rotation of the spindle about the bearing will cause a slight deflection along a line parallel to the axis of the spindle as the spindle moves on the balls which are received within irregularly shaped openings in the race due to wear. This will cause a slight movement of the lens blank during the grinding operation and this is mirrored in the finished surface. Accordingly, it is an object of my invention to provide a thrust arrangement consisting of a single point suspension, preferably operating submerged in oil so as to avoid wear.

Another object of my invention is to provide a novel method of grinding whereby the lens blank will be first grooved and then the upstanding portions between the grooves will be chipped away, thus providing for extremely rapid rough grinding, far in excess of that attainable by methods currently employed.

Further objects of my invention will become apparent from the following specific description of a preferred embodiment thereof.

In the drawings:

Figure 1 is a side elevation of a lens grinder illustrating the present invention;

Figure 2 is a view partially in elevation and partially in section taken from the front of the machine and with the guard removed in order to make the rotating and other equipment visible, the figure being partially broken away to show the traversing mechanism;

Figure 3 is a partial side elevation of the machine with the guard removed and is taken from the side of the machine opposite to the side shown in Figure 1;

Figure 4 is a detailed elevational view showing control mechanism associated with the lap spindle;

Figure 5 is a sectional view showing the improved chuck or lens holder of the present invention;

Figure 6 is a schematic view illustrating the operation of the lens picker;

Figures 7-11 are diagrammatic views illustrating the method of my invention; and

Figure 12 is a diagrammatic view showing an arrangement for raising and lowering the abrading element spindle.

Referring first to Figure 1, the machine comprises a standard spindle rotating mechanism generally indicated by the numeral 2 which may be purchased from a manufacturer of machine tools. A standard drill press unit may be used for this purpose. The spindle is indicated at 3 and the motor which drives the spindle is indicated at 4. Mechanism is provided for raising and lowering the spindle 3 and in the embodiment illustrated, this includes a rack and pinion arrangement shown diagrammatically in Figure 12 which is actuated through a hand lever 5 which may be adjustably counterweighted as shown in Figure 1. This is part of the standard drill press equipment. Encircling the spindle 3 and movable vertically therewith is a stop arrangement generally indicated at 6 which includes a threaded member 7 which is attached to a bracket 8, movable with the spindle 3 in a vertical direction. An

adjustable stop 9 is threaded on the member 7 and is secured in position by a locking nut 10. A projection 11 is provided on the machine frame against which the stop 9 comes into engagement to limit downward travel of the spindle 3. This adjustment controls the lens thickness as will be more fully hereinafter described.

Attached to the spindle 3 is a lap 12 (Figure 2) which, in the embodiment illustrated, has an annular grinding surface 13 which may be formed of diamond particles embedded in a matrix. The lap 12 is secured to the spindle 3 by a conventional Morse taper chuck arrangement as shown.

Mounted upon an upright column 14 which constitutes the main connection of the machine to its base is a bracket 15 which supports the lens holder and its associated mechanism, including the mechanism for rotating the lens holder and the mechanism for adjusting the position of the lens holder with respect to the lap. A crank mechanism (not shown) with associated rack and pinion members is provided for raising and lowering the bracket 15 and the mechanism which is carried by it.

25 A plate 16 is attached to the bracket 15 and is fixed with respect thereto. The plate 16 is provided with ways 17 and 18 which are bolted thereto as shown in Figures 1 and 3. A plate 19 is positioned for transverse movement along the ways 17 and 18, being guided by dovetailed elements 20 and 21 which are secured to the plate 19 and interfit between the ways.

30 The plate 19 may be moved transversely with respect to the lap spindle 3 by mechanism which will be now described with particular reference to Figures 2 and 3. A bearing 22 is attached to the plate 19, being secured thereto by bolts which are not shown in the drawing. An adjusting screw 23 is received within the bearing 22 and is provided with collars 24 and 25 which are fixed to the shaft 23. A threaded block 26 is bolted to the plate 16 and this block receives the threaded end of screw 23. A knurled hand wheel 27 is provided for rotation of the screw 23.

35 As will be seen from examination of the Figure 2, the axis of rotation of the spindle 3 which carries the lap 12 is disposed in a vertical plane and the plate 19 which is disposed in a vertical plane parallel to the axis of rotation of the spindle 3 may be moved with respect thereto by rotation of the hand wheel 27 which effects a movement of the plate 19 through the block 26 and the threaded end of the screw 23. The lens holder and its associated mechanism are carried by plate 19 and by adjustment of plate 19 transversely with respect to the axis of rotation of the lap, it is possible to bring the lens blank and lap into proper transverse relationship for either concave or convex grinding with the line of contact between the lap and lens passing through the axis of rotation of the blank.

40 Referring again to Figure 2, the lens holder or chuck is indicated at 28. The chuck is shown in section in Figure 5. It comprises a body 281 which has a central bore 282. It will be noted that the opening 283 in one end of the chuck is larger than the opening 284 in the opposite end. This provides for the reception of lenses of two different sizes, such as 50 mm. in opening 283 and 54 mm. in the opening 284. Soft compressible gaskets 285 and 286 of rubber or other material are provided in the openings 283 and 284 respectively. This provides sufficient frictional engagement between the lens blank and holder to 45 permit grinding without the use of adhesives or

mechanical holding mechanism for the lens blank, the lens blank being preferably wetted with water prior to insertion into the chuck to enhance the engagement. Set screws 287 are provided for holding the chuck on the chuck spindle 29. The spindle 29 is received within ball bearings 30 and 31, the housings of which are fixed to a plate 32 by means of mounting brackets 33 and 34. The plate 32 is pivoted to a plate 35 which is welded to a plate 36 disposed parallel to and in surface engagement with the plate 19. (See Figure 3.)

The plate 36 is attached to the plate 19 and moves with it and is also arranged for pivotal movement with respect to plate 19 so that the plate 36 which carries the lens blank chuck and its associated mechanism may be rotated about a pivot 37 which joins plates 19 and 36. The axis of pivot 37 extends substantially at 90° to the plane of plates 19 and 36 and substantially intersects the axis of rotation of the chuck or work holder spindle 29 substantially at the upper surface of the chuck 28 as shown in Figure 2. By having the pivot point so positioned, it is possible to adjust the angle of curvature to be formed on the lens blank without changing the transverse adjustment of the plate 19 by use of hand wheel 27. This makes the machine versatile in operation with a minimum of adjustment.

In order to effect a movement of the plate 36 and its associated mechanism about the pivot 37, an adjusting mechanism is provided which is shown in Figure 2. It is similar to the mechanism shown in the same figure for imparting a transverse motion to the plate 19 in the ways 17 and 18. It consists of a bearing 38 which is pivoted to the plate 19. A threaded block 39 is pivoted to the plate 36, and a threaded adjusting screw 40 passes through the block 39 and is received within the bearing 38, collars being provided affixed to the screw 40 to engage opposite ends of the bearing 38. A knurled hand wheel 41 is fixed to the end of the screw 40. By rotation of the hand wheel 41, it is possible to rotate about the pivot point 37 plate 36 which carries plate 32 to which the lens chuck 28 and its spindle 29 are fixed. Thus the angle of attack between the lens to be ground and the lap may be adjusted to produce the desired curvature on the lens. The axis of the lap spindle 3 is substantially vertical and is not adjustable. When the axis of the lens chuck spindle 29 is parallel to the axis of the lap spindle 3, a plano surface will be generated on the blank, and as the axis of the lens chuck spindle is inclined with respect to the axis of the lap spindle the curvature of the surface generated upon the lens blank will vary. This is true either in the formation of concave or convex surfaces. The motion of rotation of the lens chuck spindle 29 about the pivot point 37, the axis of which is disposed to intersect the axis of rotation of the spindle 29 substantially at the surface to be generated on the lens is possible regardless of the adjusted position of the plate 19. This is essential, for the cutting line of the lap 12 must be adjusted so that it passes through the axis of rotation of lens blank regardless of curvature being generated upon the lens and regardless of whether a concave, convex, or plane surface is being formed.

As previously mentioned, the plate 35 is connected to the plate 36 and is disposed normal to the plane of plate 36. The plate 32 is secured to the plate 35 by means of a pivot connection 42. Thus it is possible to effect a limited rotation of the plate 32 which carries the lens chuck

spindle 29 with respect to the plate 35 about the pivot 42. This limited rotation is effective, of course, for adjusting the axis of rotation of the lens chuck spindle laterally with respect to the axis of rotation of the lap spindle 3 to bring the cutting surface of the lap into engagement with the lens blank on both sides of the axis of rotation of the lens, accomplished by bringing the plane of rotation of the lens chuck spindle substantially into the plane of rotation of the lap spindle. The adjustment is effected through mechanism which is best shown in Figure 3. It consists of a bearing 43 which is pivoted to the plate 32. A pivoted threaded block 44 is affixed to the plate 35. An adjusting screw 45 passes through the bearing 43 and is received within the screw threaded block 44, collars being provided on the screw 45 on opposite sides of the bearing 43 to prevent axial movement of the screw. A knurled hand wheel 46 is provided for rotation of the screw 45. Upon rotation of the hand wheel 46, the screw 45 moves through the block 44 pivoting the plate 32 with respect to the plate 35 about the pivot point 42. The pitch of the thread on the spindle 45 is relatively fine in order to effect minute movement of the spindle 29 to bring the lens blank carried in the chuck 28 into proper relationship with respect to the cutting surface of the lap 12.

As shown in Figure 2, the spindle 29 rotates in bearings 30 and 31. The lower end 47 of the spindle 29 is provided with a thrust arrangement which consists of a single ball 48 which is received within an opening within the lower end 47 of the spindle 29. The ball 48 is received within a cup 49 and the cup is held in adjusted position by means of an adjusting screw 50 which is threaded into an angle bracket 51 which is bolted to the plate 32. A lock nut 52 is provided for holding the adjusting screw 50 in proper adjusted position. The cup 49 is preferably filled with oil to a point above the lower end of the spindle 47 in order to lubricate the ball thrust. With this arrangement all of the thrust is taken by the ball 48 and there is, therefore, absolutely no vibration of the lens holder 28 in an axial direction and concomitantly there is no vibration of the machine. As heretofore mentioned, any vibration of the lens holding and rotating mechanism results in the generation of an irregular surface on the lens, for axial movement of the spindle 29 will result in a variable depth of grinding irregularly over the surface.

A motor 53 is mounted upon the plate 36 and serves to drive the spindle 29 through a belt 54, the spindle 29 being provided with a pulley 55 and the shaft of the motor 53 being provided with a pulley 56 about which the belt 54 is trained.

The lens picker and braking arrangement is shown in Figures 2 and 3. The lens picking mechanism is mounted within a fluid tight receptacle 57. A standard 58 is attached to the bottom of the receptacle 57 and to this standard 58 is attached an arm 59 which is free for rotation about a projecting stud 60 and is also free for limited rocking movement with respect thereto, the opening in the arm 59 through which the stud 60 passes being enlarged to permit such movement. An operating handle 61 is provided and this is attached to one end of the arm 59 by means of a nut 62, with the end of the handle 61 being shouldered and threaded to receive the nut. The opposite end of the arm 59 carries a suction cup 63 which is secured to the arm by means of

a stud 64 and a nut 65, the stud being attached to the suction cup 63.

A bracket 66 is attached to the receptacle 57 and serves as a table to receive the lens "L" (see Figure 6) when the same is discharged from the suction cup 63. This discharge is effected by means of an extraction plate 67 which lies in the path of movement of the lens held by the suction cup. When the handle 61 is rotated from a position above the lens chuck to a position over the table 66, the lens will come into engagement with the extraction plate 67 and as further rotation is imparted to the handle 61, the suction cup will slide over the lens, leaving the same on the table 66. The table 66 is generally of a width less than the diameter of the blank, as seen in Figure 6, to permit the blank to overlie the table and provide for convenient grasp by the operator. The table may be made larger, however, and a slot provided to permit the operator to get his index finger below the blank for removal of the blank from the table.

Since rotation of the spindle 29 must be stopped prior to removal of the lens blank from the holder 28, mechanism is provided for braking the rotation of the spindle 29 after the motor 53 has been de-energized. This mechanism is preferably directly combined with the lens picking mechanism so that the operator can, with a simple motion, first effect a braking of the spindle 29, and then perform the lens picking operation.

The brake arrangement is shown in Figures 2 and 3 and consists of a brake drum 68 which may be in the form of a V-pulley which is affixed to the lens chuck spindle 29. A brake band 69 partially encircles the brake drum 68 and is attached to an arm 70, which is pivoted at 71 to a pivot plate 72, pivoted at 73 to a bracket 74 attached to plate 35. An operating link 75 is pivoted to the plate 72 at the point 76. An actuating plate 77 is pivoted to the receptacle 57 by a bolt 78. The link 75 is pivoted to the actuating plate 77 by a bolt 79. An elevating surface 80 is provided on the actuating plate 77 and the plate 77 is recessed to receive the handle 61. The end of the receptacle 57 is cut away at 81 to permit the handle 61 to move into the recess in the actuating plate so that the cover for the receptacle may be moved into closed position.

The lens blank and lap are supplied with a coolant during the abrading operation and this supply should be cut off when the grinding is complete to permit the picking of the lens. Also the motor which rotates the lens chuck spindle should be de-energized upon completion of the abrading operation on each blank. The following mechanism is effective for performing the combined functions of automatically establishing and discontinuing the supply of coolant for the lens and lap and power for the lens chuck spindle motor, coincident with the movement of the lap spindle into and out of operating position.

The mechanism is shown best in Figures 1 and 4. The coolant which may be an oil and water emulsion is fed by a pump from a source of supply, which is not shown but which may be in the form of a small tank, through a flexible line 82. A manual control valve 83 is provided in the line 82 to regulate the pressure of the coolant supplied to line 84. A mechanical valve 85, normally spring closed, is provided which is actuated by a controller 86 (Figure 4) which is pivoted at 87 to an extension line 88 leading from the valve 85. The controller 86 engages a pin 89 which is attached to a spring urged 75

closing plunger 90, which controls the opening and closing the valve 85. A cam 91 is attached to the lever 5, the cam 91 being provided with a lobe 92 effective for depressing the controller 86, thereby rotating it about the pivot point 87 and pulling the plunger 90 forward, opening the valve 85 and permitting coolant to pass from the line 84 through the valve 85 and into a line 93 which enters the receptacle 57 and terminates in a nozzle 94 (Figure 2) which directs the coolant to the surface where the grinding element engages the lens blank under treatment. A return line R connects with the supply tank.

Also associated with the lever 5 is a cam 95 which is effective for controlling the energization of the lens chuck spindle motor 53. The cam 95 actuates a normally open microswitch 96. When the lever 5 is moved to bring the spindle 3 into operating position, the cam 95 will force 20 the microswitch plunger 97 inwardly and this will make electrical contact for a magnetic switch 98 which effects energization of the motor 53. Thus when the lever 5 is moved downwardly, the motor 53 is started and, when the lever 5 is returned to its normal position, the motor 53 is de-energized.

If desired, a light or other signal may be provided to indicate to the operator the fact that a lens blank has been completely ground. This arrangement is shown in Figure 1 where the stop 9 is associated with an operating arm 99 to actuate a microswitch 100 which controls a lamp 101 in the line of vision of the machine operator. The arm 99 is pivoted as indicated at 102 and has 30 a portion 103 which projects into the path of the stop 9, there being provided a radial extension 104 on the stop 9 which is adapted to engage the portion 103 and rock the arm 99 about the pivot 102, elevating the plunger 105 of the microswitch 100. Thus, as the lever 5 is rotated, bringing the spindle 3 into operating position, the stop 9 moves therewith since it is attached to the bracket 8. The stop 104 will engage the arm 99 when the grinding operation has been completed, closing microswitch 100 and completing the circuit for light 101. An adjusting screw 106 is provided on the arm 99 so that the switch 100 will be actuated only upon the completion of the grinding operation with the spindle limiting stop 9 in engagement with the projection 11 or closely adjacent thereto, as the operator may prefer.

As shown in Figure 1, the lid 107 of the receptacle 57 is hinged and is arranged to be opened automatically by rotation of the operating lever 5. A collar 108 is attached to the lever 5 and a cable 109 is connected to the collar 108 and the lid 107. Thus when the lever 5 is rotated to bring the spindle 3 into operating position, the lid is closed and when the lever 5 is returned to the position shown in Figure 1 upon completion of the grinding cycle, the lid 107 is automatically raised. When the lid is lowered, it will not be possible to elevate the actuating plate 77 of the brake mechanism, thus insuring that the brake will not be applied until the grinding operation has been completed and the spindle 3 elevated, raising the lid 107.

In the operation of my device, a rough blank to be ground is inserted in the lens chuck 28 and the operating lever 5 is brought down, rotating the cam 95 and actuating the microswitch 96, starting the motor 53 for the lens chuck spindle 29. As rotation of the operating lever 5 continues, the cam 92 engages the controller 86 which opens the valve 85 and lubricant is fed

from the line 82 into the vicinity of the rough blank under treatment as shown in Figure 2.

The lap spindle motor 4 is continuously operating. As the operating lever 5 is rotated further, the annular lap 12 is brought down into engagement with the rough blank. In my preferred embodiment as shown in the drawings, the chuck 28 is rotated between 2,500 and 3,000 R. P. M. in one direction and the lap is rotated at about 4,000 R. P. M., preferably in the opposite direction to the direction of rotation of the chuck 28.

The lens chuck spindle 29 is adjusted by rotation of the hand wheel 27 so that the cutting line of the lap 12 intersects the rough blank along a line which passes through the axis of rotation of the lens blank. This adjustment once made generally need not be remade so long as blanks of the same diameter are being operated upon. When the sizes of the blank or the lap are changed, then this adjustment must be remade. Also when changing from a concave to a convex surface in the grinding, adjustment must be made so as to bring the proper portion of the lap into engagement with the rough blank. In convex grinding as shown in Figure 2, the axis of rotation of the lens blank is to the right of the axis of rotation of the lap and in concave grinding a lens of similar curvature, a corresponding position to the left of the axis of rotation of the lap would be assumed by adjustment of the hand wheel 27.

The second adjustment which is effected through the hand wheel 41 which rotates the spindle 29 about the pivot point 37, changes the curvature or radius formed on the rough blank in the grinding operation, by rotating the lens chuck spindle about the pivot 37. This adjustment, of course, is the same for both concave or convex grinding and would also be used in adjusting the machine to form a plano surface where the vertical axis of the lap would be parallel to the axis of the lens chuck spindle.

In the event the lap 12 is not cutting throughout the entire curvature of the blank, i. e. along a line extending from edge to edge of the blank and intersecting the axis of rotation of the blank, then the hand wheel 46 will be rotated to pivot the spindle 29 about the pivot 42, to bring the lens chuck spindle and the lap spindle into positions where their axes fall in a common plane. By making this adjustment, it is possible to cut on the entire surface of the blank upon approximately each one-half revolution of the blank and thus materially speed up the cutting operation over the prior practice where the lap merely cuts along a line extending from the center of the blank to the periphery. With this adjustment also, it is possible to obtain a true spherical curvature on the surface of the lens blank and avoid the defect which commonly occurs with the prior art machines known as a "double curve" or nonspherical surface which extends from the center of the blank out toward the periphery thereof.

The machine being adjusted to effect the proper grinding, the operating lever 5 is brought down and the blank is ground. The motion of the lever 5 is arrested by the stop 9 which comes into engagement with the projection 11 on the machine frame. At the same time, the extension 104 on the stop 9 engages the arm 103 of the light control mechanism, depressing the microswitch 105 and energizing the light 101. This signals the operator, indicating that the opera-

tion has been completed. Thereupon, the operator reverses the rotation of the lever 5, the lid 101 is raised, and the valve 85 is closed, being normally moved to that position by a spring. The cam 95 comes to a position where the switch 96 has its operating arm in outward position and the motor 43 is no longer energized.

The operator now grasps the handle 61 and elevates it while in engagement with the actuating plate 71, applying the brake 69 to the spindle 29 through the link 75, pivot plate 72 and arm 70. The application of force is continued by the operator until he observes that the spindle has stopped rotating. This is substantially instantaneous. He then disengages the handle 61 from the braking mechanism and rotates the handle to the right as shown in Figure 2 until the suction cup 63 is in a position where it overlies the ground blank which is received in the chuck 28. A rocking movement is then imparted in an upward direction to the handle 61 about the stud 60 bringing the suction cup 63 into engagement with the ground blank. Thereafter the handle 61 is lowered, pivoting the same about the stud 60 and lifting the lens blank out of the chuck 28, the same being held onto the suction cup 63. The handle 61 is then rotated to the left as shown in Figure 2 and the lens blank is brought into a position overlying the table 66. Further motion of the handle to the left with the lens blank resting on the table 66 brings the lens blank into engagement with the extractor plate 67 and as further motion to the left is effected, the lens and suction cup are separated and the lens blank is removed by the operator.

This brings the operating handle into position adjacent the opening 81 in the receptacle 67 and the handle is slipped within the opening 86 in the actuator plate 71, ready for the application of the brake upon completion of the next cycle of operation of the machine.

The method of my invention is illustrated diagrammatically in Figures 7 to 11 inclusive. When generating a surface on a lens blank or the like, the lens blank has a surface speed which varies from a minimum at the center to a maximum at the periphery of the blank. Referring to Figure 7, for example, the surface speed at the point 109 will be substantially zero. Along the line 110, the blank will have an increased surface speed and at the outer periphery 111 it will assume its maximum surface speed.

I have found from careful study of the grinding operation performed on glass lens blanks that if the surface is first scored in much the same manner that a stonemason scores his work and is then engaged by abrasive particles attacking the work at an angle to the direction of the grooves which are formed, the glass is chipped away in small bits in much the same fashion as a stonemason performs his work, and the speed of grinding is materially increased. This chipping action is best accomplished by so adjusting the surface speed of the blank with respect to the linear speed of the lap as to have the individual grit particles of the lap describe curved paths which are spaced at the periphery of the blank and simultaneously bringing abrading particles into engagement with the glass between the grooves and at an angle to the grooves to chip away the glass, simultaneously forming new spaced grooves, the glass between which is similarly engaged by abrasive particles and chipped away. This action is diagrammatically illustrated in Figures 8, 9, 10 and 11.

In Figure 8, there is shown a lap 112 having an abrading surface 113 attached thereto. I have diagrammatically illustrated in Figure 8 two abrasive points 114 and 115 on the abrading surface 113. The surface will be composed of many thousands of abrasive particles, such as diamonds; only two have been shown in Figure 8 for purposes of illustrating the action which occurs in my process of grinding.

Referring now to Figure 9 and assuming that the abrading surface 113 has a diameter of 3" and the lens blank 116 has a diameter of about 2" and that the lap is rotated at approximately 4,000 R. P. M. and the lens blank at about 2,500 R. P. M., the direction of rotation of the lens blank 116 being opposite to the direction of rotation of the lap 112 as shown by the arrows in Figure 9, a point 114 on the abrading surface 113 will describe a curved path as shown by the solid line 117 in its movement from the center of rotation 118 of the blank 116 to the periphery 119 thereof. In Figure 9, seven paths have been indicated by solid lines. The spacing between the paths will depend upon the speed of translation between the lens blank and the lap. It will be noted that the paths 117 each emanate from the axis of rotation 118 of the blank and move arcuately therefrom to the periphery 119 of the blank. The amount of movement is less at the center of the blank than at the periphery because, as previously stated, the surface speed increases from zero at the axis of rotation of the blank to its maximum at the periphery of the blank and the translatory motion depends upon the relative speed between any point on the surface of the lap moving over the lens blank and the speed of movement of the surface traversed by such point in its travel from the axis of rotation to the periphery of the blank. The paths are shown widely spaced in Figure 9. In actual practice, they will be very closely positioned and they will form grooves as indicated at 120 in Figure 11. As a matter of fact, the spacing will generally be only slightly greater than in the average particle size of the grit in the abrading element 113.

Since the abrading surface 113 engages the blank from edge to edge as shown in Figure 9, the abrasive particles 114 and 115 will form paths 121 shown in dotted lines in Figure 9. It will be noted that these lines are curved the same as the lines 117 and intersect the lines 117 at an angle which varies from the periphery toward the center of the blank. The intersection of the lines is illustrated in Figure 10. The abrasive particles when travelling along the paths 121 will chip out the glass between the lines 117 (remembering that the lines are closely spaced) and new grooves will be formed along the lines 121. As the blank is rotated, the lines 121 will be crossed by abrasive particles moving along lines 117 and the glass therebetween will be chipped out.

Reference is now made to Figures 10 and 11 where the grooves cut along the lines 117 by the particles 114 and 115 are shown as being intersected by grooves cut along lines 121. It will be noted that the lines 121 cross the lines 117 at an angle. The abrasive particles 114 and 115 which engage the surface of the lens blank chip out the glass between the grooves formed by the abrasive particles and, at the same time, they form new grooves which are chipped out when the blank is rotated to a position where the abrasive particles are describing opposite paths

of travel. Thus, there is simultaneously effected a formation of grooves and a chipping away of the glass disposed between the grooves. In Figure 11 there is diagrammatically illustrated 5 the grooving effect obtained where the lens blank has made less than one complete revolution. Here the grooves 120 have not been intersected on the portion disposed to the left of the axis of rotation 118 of the lens blank but have been on the portion disposed to the right of the axis.

I have obtained unusually high grinding speeds by use of my method of grinding in which the lap engages the blank from edge to edge thereof and passes through the center or axis of rotation of the blank, rotating the blank at a substantially higher surface speed than heretofore practiced in the art. For example, using a surface speed of 2,500 revolutions per minute with a 2" blank and 4,000 revolutions per minute with 10 a 3" lap, I am able to abrade away a full millimeter of glass in approximately 3 to 5 seconds; whereas, with the prior grinding machines practicing the conventional process of grinding, removal of one millimeter of glass would require 15 from 40 seconds to 60 seconds, using the same type of glass, the same lap speed and the same grit size but rotating the blank at a substantially lower speed, in the order of 400 revolutions per minute.

20 While I do not wish to be limited to the foregoing theory which I believe to be responsible for the improved results, it is a plausible explanation and has been found capable of being repeatedly reproduced in actual practice.

25 While I have illustrated and described a preferred embodiment of my invention, it is understood the same may be otherwise embodied and practiced within the scope of the following claims.

30 I claim:

1. In an abrading machine, a rotatable work holder, a rotatable abrading element holder, means for relatively moving the work holder and abrading element holder transversely, means for relatively inclining the axes of rotation of said holders in a substantially common plane, and means for relatively inclining said axes of rotation in a second plane disposed at an angle of substantially 90° with respect to said first plane.

35 2. In an abrading machine, a rotatable work holder, a rotatable abrading element holder, means for moving the work holder transversely with respect to the abrading element holder, means for pivoting said work holder with respect to said abrading element holder in one plane, means for pivoting said work holder with respect to said abrading element holder in a second plane at substantially 90° with respect to the first mentioned plane, and means for moving said holders relative to one another to bring said abrading element into abrading relationship with respect to a work piece received in said work holder.

40 3. In an abrading machine a rotatable abrading element holder rotatable about a substantially vertical axis included in a vertical plane, a work holder rotatable about an axis substantially included in said plane, means for pivoting said work holder with respect to said abrading element holder about a pivot axis which extends substantially at 90° to said plane and substantially intersects the axis of rotation of said work holder substantially at the surface to be abraded, means for pivoting said work holder for adjustment in a second plane disposed at substantially

90° with respect to the first mentioned plane, and means for moving said abrading element holder toward said work holder in a direction along the axis of rotation of said abrading element holder.

4. In an abrading machine having a rotatable annular abrading element and a rotatable work holder, the combination of means for relatively moving the abrading element and the holder transversely of the axis of rotation of the abrading element to bring the abrading element into engagement with a work piece in the work holder along a line extending through the axis of rotation of the work piece, means for pivoting the work holder about a pivot whose axis extends substantially perpendicular to the axis of rotation of the work holder and substantially intersects the axis of rotation of the work holder substantially at the surface of the work piece to be abraded to adjust the angle of attack between the abrading element and the work piece to vary the radius of curvature formed on the work piece, means for pivoting the work holder about a second point to adjust the axis of rotation of the work holder laterally with respect to the axis of rotation of the grinding element to bring said axes into a substantially common plane, and means for relatively moving the grinding element and work holder along the axis of rotation of one of said elements to bring the abrading element into working position with respect to the work piece.

5. In a lens grinding machine, the combination of a rotatable spindle carrying a lens blank chuck, a brake for said spindle, brake actuating means, a lens picker for removing a lens blank from said chuck upon discontinuance of rotation of said spindle, an operating handle, and means connecting said handle to said brake and to said lens picker, said handle being alternately operable to apply said brake and to effect picking of said lens upon completion of the braking of the spindle.

6. In a lens grinding machine, the combination of a rotatable spindle carrying a lens blank chuck, a brake for said spindle, and actuating means for said brake comprising an arm for applying tension to said brake, a pivot plate to which said arm is pivoted, a link pivoted to said pivot plate, a pivoted actuating plate to which the link is pivoted and an actuating handle engageable and disengageable with said actuating plate to rock said actuating plate about its pivot to apply tension to said brake through said link, pivot plate and arm.

7. In a lens grinder, a receptacle in which the grinding is effected, a hinged closure for said receptacle, a rotatable work holder disposed within said receptacle, means for braking the rotation of the work holder including an operating handle, said receptacle having a handle receiving recess therein, said recess being closed when said closure is in applied position, a grinding element disposed within the receptacle, means for moving the grinding element into and out of grinding position with respect to the work holder, and means associated with said moving means for applying said closure when said grinding element is in grinding position and for removing said closure when the element is out of grinding position, whereby said brake operating handle cannot be actuated during grinding.

8. In a lens grinder, a receptacle in which the grinding is effected, a hinged closure for said receptacle, a rotatable work holder disposed

within said receptacle, means for braking the rotation of the work holder including an operating handle, said receptacle having a handle receiving recess therein, said recess being closed when said closure is in applied position, a grinding element disposed within the receptacle, means for moving the grinding element into and out of grinding position with respect to the work holder, means associated with said moving means for applying said closure when said grinding element is in grinding position and for removing said closure when the element is out of grinding position, whereby said brake operating handle cannot be actuated during grinding, and a motor for rotating the lens blank chuck, means for energizing the motor when the closure is applied and for de-energizing the motor when the closure is removed, whereby braking can be effected only after the motor has been de-energized.

9. In an abrading machine having a rotatable abrading element holder, means for rotating the abrading element holder, a rotatable work holder, an electric motor for rotating the work holder, means for moving the work holder and the abrading element holder relative to one another to bring the abrading element into abrading relationship with the work to be ground, and means for supplying coolant to the abrading element and the work, a normally closed valve for controlling the coolant supply, a normally open switch for controlling the electric motor, and a combined cam carried by the means for moving the work holder and the abrading element holder relative to one another for actuating said valve and said switch to supply coolant and rotate said work holder upon movement of said moving means to bring the work holder and abrading element holder into operative abrading position.

10. In an abrading machine, a rotatable work holder, a rotatable abrading element holder, a plate disposed substantially parallel to the axis of rotation of said abrading element holder, a second plate disposed at an angle with respect to said first plate, said first and second plates being pivotally connected to afford pivotal adjustment of the second plate in a plane at an angle to the plane of the first plate, and said rotatable work holder being mounted on said second plate for movement with both said first and second plates collectively and with said second plate independently, means for pivoting said first plate about a pivot whose axis extends substantially at 90° from said first plate and substantially intersects the axis of rotation of said work holder substantially at the surface of the work to be abraded to adjust the angle of attack between the abrading element and the work piece and thus vary the radius of curvature formed on the work piece by the abrading element, said pivotal connection between the first and second plates affording adjustment of the work holder to bring the abrading element into engagement with the work piece along a line extending from edge to edge thereof.
